UNITED STATES PATENT OFFICE.

JACOB CODOS, OF BROOKLYN, NEW YORK, ASSIGNOR TO CONTINENTAL PAPER & BAG MILLS CORPORATION, OF NEW YORK, N. Y., A CORPORATION OF DELAWARE.

FINGER BAG.

Application filed December 20, 1924. Serial No. 757,102.

My invention relates to bags which, in addition to their other functions, may serve as shopping bags and has for its object to provide a novel and simple arrangement of handle whereby the bag may be carried about and whereby the seal flap of the bag and the handle are fixed in their operative positions. Other objects of the invention will appear from the description hereinafter and the 10 features of novelty will be pointed out in the claims.

In the accompanying drawing, which shows an example of the invention without defining its limits, Fig. 1 is a face view of the bag with the seal flap in its open position; Fig. 2 is a similar view showing the seal flap closed and the handle in connection therewith; Fig. 3 is a corresponding view showing the handle about to be adjusted to 15 its operative position; Fig. 4 is a sectional view on the line 4—4 of Fig. 3; Fig. 5 is a sectional view on the line 5—5 of Fig. 2, showing the handle and flap in their connected relation, and Fig. 6 is a detail section 20 on the line 6—6 of Fig. 2.

As shown in the drawings, the bag comprises a body of any suitable shape and dimensions, open at one end and closed at the other, and consisting of a front 10 and a back 25 11, the detail construction of the body being of any conventional type and forming no part of the present invention. A seal flap 12 extends from the front 10 of the body and preferably comprises an integral continuation thereof, said flap 12 being foldable in a transverse crease 13 over the back 11 to close the open end of the bag in the usual way. The bag further includes a handle 14 30 preferably made of heavy paper or cardboard which should be quite stiff but still flexible. The handle 14 has a suitable opening 15 for the accommodation of the fingers of the person carrying the bag, said handle being attached at one end, as by pasting, to the back 11 of the body; the handle 14 is 35 so located and dimensioned that, in its operative position, it projects beyond the closed end of the bag with the opening 15 in a position of ready accessibility as shown in Fig. 2. In addition, the bag includes a means 40 combined with the flap 12 whereby it may be connected with the handle at will to fix both the flap and the handle in their operative positions. As shown in the drawings, 45 this means comprises a band 16 lying upon

the outer surface of the flap 12 and having its opposite ends fixed thereto as by pasting, the intermediate portion of said band between its fixed ends being free end disconnected from the flap and slightly raised or 60 spaced therefrom as shown in Fig. 6.

In the operative position of the parts, the flexible handle 14 projects from the body over and in surface engagement with the outer surface of the seal flap and beneath 65 the band 16, as shown in Figs. 2 and 5. To facilitate the insertion of the handle 14 beneath the band 16 and its withdrawal therefrom, the handle is provided with spaced score lines 17 and 18 to provide hinges at 70 such lines. As shown in Fig. 1, the score line 17 is located on the handle near its point of attachment to the body and constitutes a hinge on which said handle is pivotally movable, while the score line 18 is located at 75 an intermediate point on the handle and permits the latter to be flexed, as indicated in Figs. 3 and 4 for insertion beneath and withdrawal from the band 16 at will.

When the flap 12 and handle 14 are in 80 connection with each other through the medium of the band 16, the flap 16 is fixed in its closed position and at the same time the handle 14 is properly maintained in its operative carrying position. The arrangement is such that the seal flap 12 is not slotted or otherwise weakened in any way and thus retains its full strength and is thereby 85 capable of resisting the strains to which it may be subjected when the bag is full and 90 is being carried by the handle; at the same time the band 16 by being attached upon the surface of the flap provides a strong connecting bond between the flap and the handle 95 when the latter is in its operative position 100 whereby any strains placed upon the loaded bag are adequately resisted without injury either to the bag or to the handle. Furthermore, the novel construction, by doing away with the necessity for the customary 105 slitting operations, avoids the use of complicated machinery in the manufacture of the bag and reduces the cost of production to a minimum. The novel features are capable of being incorporated in bags of existing type or in specially constructed bags 110 regardless of size and shape.

I desire to point out some of the details of the structure shown in the drawings and the advantages arising therefrom. The han-

dle 14 is preferably made of considerable width so that it will reinforce the upper portion of the bag and in order to strengthen the upper edge of the bag the band 16 is quite long, just short of reaching the extreme side edges of the bag. It is also to be noted that thereading the handle 14 between the flap 12 and the band 16 is quite simple. When the handle is brought to the position shown in Figs. 3 and 4 downward pressure on the high point (represented by the hinge 18) results in the handle being flattened and its end thrust between the flap 12 and the band 16.

15 Various changes in the specific form shown and described may be made within the scope of the claims without departing from the spirit of my invention.

I claim:

20 1. A finger bag comprising a body, a closure flap extending from the front of the body and foldable over the back thereof to close the open end of the bag, a band secured to the outer surface of said flap and having its ends secured in proximity to the edges of the flap, a handle having its lowermost edge secured to the bag body and a finger opening at its free end, said band normally standing away from the 25 surface of the flap to permit the ready threading of the end of the handle under the band, said band and said handle locking the bag and providing a reinforce across the top thereof.

30 35 2. A finger bag comprising a body, a closure flap extending from the front of the body and foldable over the back thereof to close the open end of the bag, a band se-

cured to the outer surface of said flap and having its ends secured in proximity to the 40 edges of the flap, a handle having its lowermost edge secured to the bag body and a finger opening at its free end, a fold line across the handle in proximity to the line of attachment thereof to the bag body, a 45 second fold line between the first mentioned fold line and the finger opening, the said handle being adapted to be folded along the fold lines to insert the end thereof under the band and its end projected through the 50 band by pressure at the last mentioned fold line.

3. A finger bag comprising a body, a closure flap extending from the front of the body and foldable over the back thereof to 55 close the open end of the bag, a band secured to the outer surface of said flap and having its ends secured in proximity to the outer edges of the flap, a handle made of a section of paper having its lowermost edge 60 secured to the bag body and an elongated finger opening at the free end thereof, fold lines on the handle between the point of attachment to the bag body and the finger opening, one of said fold lines being in 65 proximity to the point of attachment and the other in proximity to the finger opening, the handle being otherwise unperforated and being adapted to have its free end passed beneath the band by folding it at the fold 70 lines and the end thereof projected through the band by pressure at the fold line which is in proximity to the finger opening.

In testimony whereof I have hereunto set my hand.

JACOB CODOS.
